DESIGN FOR A DRESS ENSEMBLE

Anthony Traina, New York, N. Y.

Application January 6, 1944, Serial No. 112,178

Term of patent 3½ years

To all whom it may concern:

Be it known that I, Anthony Traina, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design.

Fig. 2 is the rear view of the ensemble shown in Fig. 1, and

Fig. 3 is a fragmentary front view of the dress member of the ensemble shown in Fig. 1.

The rear of the dress member of the ensemble is conventional.

I claim:

The ornamental design for a dress ensemble, substantially as shown and described.

ANTHONY TRAINA.
